UNITED STATES PATENT OFFICE.

EDWARD O. BENJAMIN, OF NEWARK, NEW JERSEY.

HYDROCARBON BURNER AND GAS GENERATOR.

Application filed April 11, 1924. Serial No. 705,813.

- My present invention is shown as embodied in a simple device adapted for use in the fire boxes of boilers or ordinary furnaces such as are used for heating houses, but the 5 device is essentially a gas producer and burner in which the actual burning of fuel oil or other liquid hydrocarbon is merely for producing initial heat which is effectively utilized to produce a water gas reaction between fluid hydrocarbon and steam, forming 10 carbon monoxide (CO) and hydrogen (H); and in normal operation it is these gases which are burned under conditions insuring practically complete combustion. As part 15 of the gas may be tapped off or all of it may be burned in the device, it is obviously adaptable for use in almost any place where generation either of heat or of fuel gas is desired.
- 20 The object of the invention is to produce a device suited to the above purpose, which may be made of almost any size or capacity which will stand up under extreme conditions of use or abuse, which will operate efficiently for the production of a completely 25 gasified mixture, which will be automatically self regulating within very wide limits and practically fool proof in the hands of unskilled users.
- 30 The device includes means for generating steam, for superheating the steam, for utilizing the steam pressure to atomize and inject fluid hydrocarbon into a reaction chamber which is maintained at high temperature and 35 wherein the reaction between the hydrocarbon and the steam is effectively promoted and for burning the gas to produce such steam and to maintain such temperature. The reaction chamber is a passage long 40 enough and having sufficient flow resistance to afford time for complete development of the water gas reaction, but self draining so as to avoid trapping or accumulation of liquids.
- 45 In normal operation the gasified mixture flows from the reaction chamber through a constricted nozzle, under pressure sufficient to produce a powerful injector jet. This jet discharges into a mixing tube having suitable 50 air draft inlets supplying substantial primary air to the mixture but not sufficient to support combustion. The partly aerated gas from the mixing tube flows to a burner beneath the steam generating boiler in heat-
- ing relation to both said boiler and said reaction chamber, the latter being preferably a helical spiral co-axial with and surrounding the boiler.
- During the preliminary stage prior to normal operation, the hydrocarbon fuel flows 60 through the reaction chamber and the injector jet into a flash pan beneath the boiler. When a sufficient amount of oil accumulates in the flash pan, the inlet valve may be closed by a float actuated by the oil level 65 in the flash pan. Upon ignition of the oil, the flame heats up the reaction chamber, steam generator, superheater, injector and other operative elements of the device until 70 steam is generated in quantities and at pressures necessary to atomize the oil, whereupon the normal water gas reaction begins.
- In normal operation the automatic regulation of the device is due partly to proportioning of the parts and partly to a novel 75 means for regulating the water supplied in accordance with the heat of the flame of the burning gas. The primary feature of the regulation referred to results from the fact that with any given rate of oil supply too 80 great a supply of steam will result in decomposing unnecessarily large amounts of water, producing incombustible carbon dioxide instead of the desired carbon monoxide. Whatever carbon dioxide is produced 85 operates in two ways. First, it represents a loss of a most important fuel constituent and, second, it tends to retard combustion. Moreover, excessive steam is itself a diluent 90 tending to retard combustion. Consequently, generation of steam in excess of what is required for the rate of fuel supply operates immediately to decrease the heat available for generating the steam. On the other hand, the critical temperature and most efficient operation having been once passed, 95 decrease of steam will operate to increase the percentage of combustible carbon monoxide and decrease the steam diluent and cause the steam to act as an oxygen carrier to intensify combustion, thereby increasing the heat of the flame.
- In conjunction with this natural self regulation, an important feature of my invention 100 is the employment of a thermo regulator for the feed water which is in close proximity to and which is operated by and in accordance with the heat of the flame to supply addi-

tional water to the boiler when the flame is too hot and to cut off water when the flame becomes too cool.

The above and other features of my invention may be more fully understood from the following description in connection with the accompanying drawings, in which

Fig. 1 is a view in side elevation of my improved unit, parts of the flash pan being broken away and in section for clearness;

Fig. 2 is a view in longitudinal section through the thermostatic water regulating valve, taken on the line 2-2 of Fig. 7;

Fig. 3 is a vertical sectional view through the unit on the staggered line 3-3 of Fig. 7;

Fig. 4 is a fragmentary sectional plan view on the staggered line 4-4 of Fig. 3;

Fig. 5 is a view in transverse section on the staggered line 5-5 of Fig. 1 and Fig. 3;

Fig. 6 is an enlarged sectional view through a portion of the retort or reaction chamber;

Fig. 7 is a top plan view of the unit.
25 My improved heater is in the form of a compact unit, comprising a base consisting of a flash pan 10 and a circular burner 13 either rigidly or integrally connected thereto. Above the burner I arrange a boiler 15 surrounded by a long spiral retort chamber 31. A tubular oil filter and vaporizer 32 and a tubular thermostatic feed water regulator 50 are secured to the retort at opposite sides. The flash pan 10 is formed with a

35 central draft opening 10', and it will be apparent that when the burner is in operation the boiler, retort, oil vaporizer, and water regulator will be exposed to the direct heat of the flame from the burner. The boiler is centrally disposed above the burner and flash pan and may be formed with an outwardly flared upper flange 15' upon which impinge flame and hot gases therefrom. The functions of the flange include deflecting 45 the hot draft and flame from the burner, and conducting heat thus absorbed to superheat the upper part of the boiler.

The annular flash pan 10 is mounted upon screw-adjustable legs 11 and it supports an 50 annular burner 13 which has laterally discharging burner orifices 14. The burner is substantially concentric with the flash pan and affords support for the water boiler 15 which is in the nature of a pot shaped receptacle having feet 16 resting on blocks 16' which are preferably of lava or other refractory material. The boiler 15 may be externally ribbed as at 17 to promote heat transference, and consists of a lower water 55 chamber 18 and an upper steam dome or drying chamber 19, a restricted opening 20 being provided in the dividing wall 21 between them. Water is admitted into the bottom of the chamber 18 from a supply pipe 60 22 through an inlet plug 23. The method of

controlling the water supply will be described hereafter.

Superheated steam escapes through apertures 24 into superheater tube 25 extending into the steam dome and cast integral with the walls thereof. From the tube 25 the steam under pressure passes into a coupling member 26, which is elbow shaped and terminates in a nozzle 27 of an atomizing injector for the liquid fuel. The nozzle projects into the Venturi tube 28 and is held in proper relation therewith by a screw coupling 29 which surrounds the suction end of the venturi and to which the hydrocarbon fuel is supplied through lateral inlet pipe 30.

70 As shown in Fig. 3, this injector is directly in the draft of flame or hot gases from the burner 13 and as shown more clearly in Figs. 1 and 7, the deflecting flange 15' is partly cut away above the injector to intensify the updraft on the latter.

75 The discharge end of the Venturi tube 28 enters the upper end of a long retort or reaction chamber 31 encircling the boiler 15 and consisting of a number of downwardly inclined coils of a progressively enlarging helical spiral. The steam jet discharging in the Venturi tube creates a powerful suction at the inlet whereby the hydrocarbon fluid is sucked into the jet, atomized and projected into the retort 31, the steam thoroughly mixing with and highly heating the atomized oil at the entrance to the retort. In this retort or reaction chamber the temperature is high enough to cause the desired decomposition of the water (H_2O) to produce hydrogen (H_2) and to oxidize the carbon (C) to carbon monoxide (CO); also methane (CH_4), etc.

80 100 The cavity within the nozzle member 26 may contain steam filtering material and a screen 27' to catch foreign particles such as might tend to clog the nozzle 27. A plug 26' in the coupling member permits the filtering material or the screen to be readily 110 removed and replaced.

I prefer to filter, preheat and to some extent vaporize the liquid hydrocarbon which is supplied to the injector through pipe 30. Preferably, therefore, the inlet pipe 30 is 115 supplied from the upper end of a vertical oil filter 32 which receives oil under pressure from a feed line 34. This oil filter, particularly the upper end thereof, is in position to be highly heated from the burner flame, and, its flow-section being large, the passage of the oil therethrough takes long enough to permit the desired degree of preheat and vaporization.

120 Any convenient filtering means might be used but I prefer the type shown herein, consisting of a tubular container 32 with an apertured pipe 35 located centrally thereof and closed at the lower end by screw plug 35'. The space between the walls of the con-

tainer and the pipe contains some suitable filtering medium such as several thicknesses of woven wire or asbestos 36 secured by wires 36'. The oil is forced or sucked into the pipe 35 through this material. A drain plug 37 may be provided for draining the filter and replacing the filtering material.

From the lower end of the reaction chamber 31 the products of reaction flow as a combustible gaseous mixture, through a tube 40, into a nozzle 41, discharging into an air mixing chamber 42 which is preferably formed as a lateral extension of the flash pan, and which communicates through two passages 43, which discharge upward into the ring burner 13, at diametrically opposite sides thereof. Air inlet openings 44 are provided in the wall of the mixing chamber 42 and manually adjustable, pivoted dampers 45 may be provided for regulating the passage of air through these openings. The powerful jet of gasified mixture escaping through the nozzle 41 acts as an injector to suck air through the openings at 44 into the mixing chamber 42, where the air becomes thoroughly mixed with the combustion gases before reaching the burner orifices 14.

As seen most clearly in Fig. 4, the draft mixture of air and gas impinges upon the apical end of a deflector 46 which divides it and causes it to flow through the diverging passageways 43 to opposite sides of the burner 13. The deflector is provided with an apron 47 extending well below the nozzle 41 and leaving only a small opening through which the initial priming liquid can flow out and through which supplemental air may be drawn in by the injector action of jet during normal operation.

For furnace installations I prefer to encase the reaction tube with an irregular or lumpy coating of fire clay, magnesia or some similar refractory cement, as indicated at 48 in Fig. 6. By this means I am able to protect the metal surface of the reaction chamber from oxidation or burning by the flame and to maintain a uniform high temperature so that the surface radiates considerable heat.

The means for thermostatically controlling the water supply to the boiler 15 is shown in Fig. 2. This consists of a tubular valve casing 50 into which water is delivered by a pipe 51 through a passage 52. The outlet from the valve casing 50 is through the pipe 52. Passage 52 is formed with a valve seat 53 in cooperative relation to a needle valve 54 which is carried by a plug 55 threaded into the end of the casing opposite the valve seat. The needle valve normally fits the seat and prevents any flow of water into the valve casing 50, and to pipe 22 which leads to the boiler, but the casing 50 is near and fully exposed to the heat of the flames from the flash pan 10, at starting, and afterwards from the burner outlets 14. The heat causes

the casing to expand thereby increasing the distance between the valve seat and the upper end where the valve stem is anchored thereby drawing apart the valve and valve seat thus leaving an opening for inflow of 70 the water. Eventually the valve stem becomes heated, and tends to expand downward to decrease the inlet opening but the valve is relatively protected from the heat by the casing and is much more effectively 75 cooled by the water supply. Hence there is always a sufficient differential expansion operating to maintain a water inlet at the valve seat whenever the casing is hot, the amount of the opening varying automatically with 80 the heat of the flame and its temperature effect on casing 50. The ranges and amounts of this governing can be predetermined by the sizes and location of the parts. The expansion differential can be increased by making the casing and valve stem of materials, such as certain alloys having high coefficients of expansion and may be further increased by making the casing of a high coefficient 85 metal and the valve stem of a low coefficient 90 metal. In order to permit adjustment of the valve 54 so that water flow may be initiated at any predetermined temperature of the casing, the valve is threaded into a screw threaded socket or recess 56 on the inside of 95 the plug 55 against resilient packing material such as 57.

It will be noted that the amount of steam required for proper operation of the device is relatively small and efficient or rapid heat 100 absorption is not a necessary characteristic of the steam generator. On the other hand, certainty of generation of steam under widely varying conditions of oil consumption and gas output is extremely important; also superheating of the steam is important. The particular arrangement shown is well adapted to combine these desirable features. The boiler is made with relatively thick walls tending to slow heat 105 transfer and the water containing portion thereof is substantially hemispherical and hence has the least possible heat absorbing surface per unit volume of the water. The certainty of steam generation approximately proportional to the flame is insured, however, by having the generator pot coaxial with concentric annular walls of flame from the orifices 14 of burner 13, one set of said orifices being directed inwardly 110 and the other set outwardly as shown in Fig. 3. Thus, the boiler affords as little chilling surface as possible to the flame. The superheating of the steam in the upper part of this same device is insured by 115 the flanges 17 and 15' against which the flame and hot products of combustion impinge and both of which are located above the level of the water. Under certain conditions the flange 17 may absorb and con- 120 125 130

duct to the pot enough heat so that the water will boil at the top edges rather than from the bottom, and in all cases the entire upper, superheated portion will be kept very hot.

The steam pressure that can occur in the generator is slight as compared with the strength of the pot, because the latter is preferably good quality cast iron with thick, well arched walls that will withstand very high pressure and also because excessive steam from the injector will impair the quality of the gas, while clogging of the injector outlet would stop the gas generation process. Moreover, a fusible plug or safety valve may be employed if desired. It will be noted that the water inlet hole at the bottom, the hole 20 in the partition and the hole 70 at the top afford opportunity for ample anchorage of the cores when the pot is made by casting.

The oil supply from pipe 34 to the filter 32, is controlled by a needle valve 60 (Fig. 5) mounted in a valve casing 61 integral with the lower end of the filter. The needle valve coacts with a valve seat 63 and is rotatably mounted in the casing 61, said casing and valve having inter-connection through relatively high pitched threads 64 operating to produce endwise movement of the valve when the latter is rotated. A float arm 66 rigidly connected to the stem of the needle valve 60 carries a float 67 normally seated in a depression 68 (Fig. 1) of the flash pan. When the oil level in the flash pan rises, the rising float 67 will swing the arm 66 rotating the needle valve 60 into closed position and shutting off the oil supply to the filter 32.

The operation is as follows: The float 67 ordinarily rests on the bottom of the pocket 68 in the flash pan 10. Consequently the valve 60 is normally open and oil flows under pressure through filter 32, passage 29, Venturi tube 28, and retort 31; thence the oil drains by gravity through the retort pipe 40, nozzle 41 and under lip 47 into the flash pan 10. As the level of the oil rises the valve 60 will close, shutting off the oil. When the oil in the flash pan has been ignited and the parts sufficiently heated by the flame, the thermostatic water valve 54 will become operative in the manner above described, and water will start to flow into the hot boiler 15. By the time the boiler is hot enough to generate steam for the injector, and float 67 will have lowered enough to open valve 60 and oil will again flow through the filter, the filter will become hot enough to preheat and partially vaporize the oil passing therethrough and the mixture passing through the Venturi tube into the retort will consist of hot steam and vaporized hydrocarbon with finely atomized oil in suspension therein. The re-

action occurring in the retort, the mixture of the products of reaction at high pressure with air, and the delivery to the burner have been described above. As the temperature rises the water gas reaction becomes more complete, the temperature of the flame in the burner increases, and more air is induced through the ports 44 until equilibrium is reached for a given rate of fuel supply. The oil is completely vaporized and the retort is operating at full efficiency, and the air inlets being properly adjusted, the mixture burns with a steady and intense blue flame.

Under conditions of equilibrium the rate of water feed to the steam generator is controlled by the thermostatic regulator. If the rate of supply of fuel is increased, the volume of flame and its heating effect on the casing 50 will operate to increase the water supply while decrease of fuel supply will have the opposite effect. Under all normal conditions, a substantial lowering of the level of the water in the boiler will result in increased superheat of the steam, less heat absorption in the boiler and more heat reaching the casing 50.

The desired reactions in the coil may be brought about more perfectly and at lower temperatures by employing a suitable catalytic agent for the retort tube and this may be applied as a coating to the interior of the tube. For instance, nickel may be employed to promote the production of methane in the breaking down process and chromium to promote the oxidization of carbon to carbon monoxide. Metals of this nickel chromium group tend to reduce the amount of free carbon and produce a cleaner burning flame less likely to cause sooty deposits. Either or both the nickel and chromium may be obtained in suitable subdivision for favorable catalytic reaction by mixing their oxides or carbonates in water with fire clay or plaster of Paris to form a mixture of suitable consistency. The interior of the coil may be then flushed with this mixture, drained and dried to produce a coating of the desired thickness, say, one-thirty-second to one-sixteenth of an inch. Then the tube may be heated to a red heat while the interior is filled with a reducing gas such as hydrogen. This will reduce the oxide or carbonate to the metal nickel or chromium in a proper physical condition for effective catalytic action for the purposes above described.

Many of the structural details, described in the specification are not at all essential to the success of the invention. For instance, the shape of the retort might be varied, other means might be utilized for controlling the flow of water and oil, for filtering the oil and for superheating the steam without departing from the spirit of the invention, which includes

any and all changes and alterations that fairly fall within the scope of the appended claims.

While the size of my device is not an essential feature and while even the relative sizes of parts may be varied within considerable limits, it is an important feature that I have succeeded in embodying in a small unit burner elements whereby a true and relatively perfect water gas reaction may be brought about. It is an essential of such reaction not merely that the atomized oil is broken down to combustible gas and free carbon, but also there should be the characteristic water reaction with the precipitated carbon or soot to form combustible carbon monoxide (CO). My construction of proportional parts is particularly adapted to make certain its proper functioning in this particular. For instance, even if the device be constructed on a scale such that the pot 15 is only five or six inches in diameter, the reaction space afforded by coils 31 will be ten feet or more in length, on the scale shown in the drawings and the conditions are such that the characteristic carbon oxygen reaction will occur somewhere between half and three-quarters of the distance from the atomizing inlet toward the outlet of the coil and this will be very evident to the eye by reason of the fact that the coil in this region will become red hot, the C plus O reaction being exothermic, that is, heat evolving. One factor in producing this result is having the tube of great diameter as compared with the capacity of the steam and oil supply device, so that although the latter may enter the coil at very high velocity and temperature, the cross-section of the tube in which they emerge will be so large proportionally that the gases will actually travel through the coil quite slowly and be exposed to the heat thereof for the relatively long time necessary to produce the above described result.

The opening below 47 between the mixing chamber and the flash pan may be provided with wire gauze for its well known purpose of preventing back firing of ignited oil of the flash pan into the mixing chamber.

I claim:

1. A heater unit comprising a burner, a steam generator arranged above the burner, a retort chamber arranged for drainage from the inlet toward the outlet, encircling the steam generator and heated by the burner, a steam injector for injecting vaporized oil into the retort, means for delivering the products of the reaction of the steam and oil from the retort to the burner.
2. A heater unit comprising a burner, a steam generator arranged above the burner, a retort chamber encircling the steam generator and heated by the burner, a steam injector through which said steam generator
3. A heater unit comprising a burner, a steam generator arranged above the burner, a retort chamber encircling the steam generator and heated by the burner, means for introducing steam and vaporized oil into the retort, means for delivering the products of the reaction of the steam and oil from the retort to the burner and means for adding air to the products of reaction before they reach the burner orifice. 70
4. A heater unit comprising a burner, a steam generator arranged above the burner, a retort chamber encircling the steam generator and heated by the burner, means for introducing steam and vaporized oil into the retort, means for delivering the products of the reaction of the steam and oil from the retort to the burner, means for adding air to the products of reaction before they reach the burner orifice and a flash pan below the burner wherein oil is adapted to be burned to prime the heater. 75
5. A heater unit comprising a burner, a steam generator arranged above the burner, a spiral retort chamber encircling the steam generator and heated by the burner, means for introducing superheated steam and vaporized oil into the retort, means for delivering the products of the reaction of the steam and oil from the retort to the burner, said means including an injector, nozzle, and air intake ports associated with the nozzle. 80
6. A heater unit comprising a burner, a steam generator arranged above the burner, a spiral retort chamber encircling the steam generator and heated by the burner, means for introducing superheated steam and vaporized oil into the retort, means for delivering the products of the reaction of the steam and oil from the retort to the burner, said means including an injector nozzle and air intake ports associated with the nozzle; means for directing products of reaction from the injector nozzle through a plurality of passageways to the burner. 85
7. A heater unit comprising a burner, a steam generator arranged above the burner, a spiral retort chamber encircling the steam generator and heated by the burner, means for introducing superheated steam and vaporized oil into the retort, means for delivering the products of the reaction of the steam and oil from the retort to the burner, said means including an injector nozzle and air intake ports associated with the nozzle; means for directing products of reaction from the injector nozzle through a plurality of passageways to the burner. 90
8. In a heater unit, a burner, a steam generator and superheater above the burner, an oil vaporizer, an elongated tortuous reaction chamber through which a commingled oil and steam mixture are caused to pass, temperature responsive means controlling the proportions and temperatures of the steam in the mixture in response to variations of flame temperature, and means for delivering the gaseous products of reaction from the reaction chamber to the burner. 95
9. In a heater unit, a burner, a steam generator and superheater above the burner, an oil vaporizer, an elongated tortuous reaction chamber through which a commingled oil and steam mixture is caused to pass, temperature responsive means controlling the proportions and temperature of the steam in the mixture in response to variations of flame temperature, means for delivering the gaseous products of reaction 100
10. In a heater unit, a burner, a steam generator and superheater above the burner, an oil vaporizer, an elongated tortuous reaction chamber through which a commingled oil and steam mixture is caused to pass, temperature responsive means controlling the proportions and temperature of the steam in the mixture in response to variations of flame temperature, means for delivering the gaseous products of reaction 105
11. In a heater unit, a burner, a steam generator and superheater above the burner, an oil vaporizer, an elongated tortuous reaction chamber through which a commingled oil and steam mixture is caused to pass, temperature responsive means controlling the proportions and temperature of the steam in the mixture in response to variations of flame temperature, means for delivering the gaseous products of reaction 110
12. In a heater unit, a burner, a steam generator and superheater above the burner, an oil vaporizer, an elongated tortuous reaction chamber through which a commingled oil and steam mixture is caused to pass, temperature responsive means controlling the proportions and temperature of the steam in the mixture in response to variations of flame temperature, means for delivering the gaseous products of reaction 115
13. In a heater unit, a burner, a steam generator and superheater above the burner, an oil vaporizer, an elongated tortuous reaction chamber through which a commingled oil and steam mixture is caused to pass, temperature responsive means controlling the proportions and temperature of the steam in the mixture in response to variations of flame temperature, means for delivering the gaseous products of reaction 120
14. In a heater unit, a burner, a steam generator and superheater above the burner, an oil vaporizer, an elongated tortuous reaction chamber through which a commingled oil and steam mixture is caused to pass, temperature responsive means controlling the proportions and temperature of the steam in the mixture in response to variations of flame temperature, means for delivering the gaseous products of reaction 125
15. In a heater unit, a burner, a steam generator and superheater above the burner, an oil vaporizer, an elongated tortuous reaction chamber through which a commingled oil and steam mixture is caused to pass, temperature responsive means controlling the proportions and temperature of the steam in the mixture in response to variations of flame temperature, means for delivering the gaseous products of reaction 130

from the retort to the burner, and a flash pan into which liquid forming in the reaction chamber is adapted to drain.

8. In a heating unit, a burner, a steam generator, a superheater chamber, a restricted passage leading from said generator to said superheater chamber, an oil vaporizer, a retort chamber, means for injecting and vaporizing oil by a jet of superheated steam into the retort chamber, means for delivering the products of reaction from the retort chamber to the burner, said steam generator, vaporizer, and retort chamber being directly exposed to the heat of the flame from the burner.

9. A heater as described in claim 8 and including thermostatic means for controlling the supply of feed water to the steam generator also exposed to the direct heat of the burner flame.

10. In a heating unit, a burner, means heated by the burner for generating water gas, a deflector at the discharge point of the water gas generating means for dividing the discharged water gas into a plurality of streams, and means for conducting one of said streams to the burner.

11. In a heating unit, a burner, means heated by the burner for generating water gas, a deflector at the discharge point of the water gas generating means for dividing the discharged water gas into a plurality of streams, and means for conducting one of said streams to the burner and means for mixing air with the water gas during its passage to the burner.

12. In a heating unit, a burner, a hot tortuous reaction chamber through which mixed steam and oil are adapted to be passed to form a water gas fuel for the burner, separate means responsive to the heat of the burner for vaporizing the oil and for superheating the steam prior to their passage through the reaction chamber and means for utilizing the superheated steam to inject the vaporized oil into the reaction chamber.

13. A heater of the class described in claim 12 characterized in that a steam generator is provided, and thermostatic means operable under the influence of the heat of the burner controls the supply of feed water to the steam generator.

14. In a heater of the class described in claim 12, said oil vaporizing means having oil filtering devices therein.

15. A gas producer and heating unit, including a circular burner, a steam generator comprising a pot disposed above the burner in position to be surrounded by the draft of flame and hot products of combustion from the burner; an oil supply and an injector discharging into a reaction chamber wherein the steam is intimately mixed with atomized oil and hydrocarbon vapor, means for controlling the proportions and temperatures of the latter to form a fuel gas for the burner, the walls of said pot presenting a minimum of heat absorbing surface relative to its capacity.

16. A gas producer and heating unit, including a circular burner, a steam generator and dryer comprising a round bottomed pot having an upper chamber with an exterior flange disposed above the burner in position to be surrounded by and to deflect the draft of flame and hot products of combustion from the burner, an oil supply and an injector discharging into a reaction chamber wherein superheated steam is intimately mixed with atomized oil and hydrocarbon vapor to form a fuel gas for the burner.

17. A gas producer and heating unit, comprising a circular burner, a steam generator comprising a pot and a reaction chamber comprising a helical coil, both disposed above and coaxial with the center of the burner whereby they are surrounded by a draft of flame therefrom, means for supplying the steam and partially vaporized and atomized oil to the upper end of said coil to cause a reaction between the superheated steam and the oil to produce fuel gas for said burner.

18. A gas producer and heating unit, including a burner, a steam generator, a superheater chamber, a restricted passage leading from said generator to said superheater chamber, an oil supply line, a heated reaction chamber wherein superheated steam and atomized oil and oil vapor are intimately mixed and react upon each other to form a fuel gas for the burner, said burner being located directly beneath said steam generator and reaction chamber to cause the flames and hot products of combustion to constantly impinge thereon, said reaction chamber having a greater heat receiving surface than said generator.

19. A gas producer and heater unit, including a burner, a steam generator upon which the flames of the burner directly impinge, means for superheating steam, means for intimately mixing atomized fuel oil with steam in the presence of heat to produce a fuel gas for the burner, said steam generator comprising a round bottomed pot to present a minimum surface per unit volume to the heating flames.

20. A flash pan and burner construction for heating units, comprising an annular flash pan having a central draft opening therein and an annular burner disposed above the flash pan, said flash pan and burner constituting an integral structure; said flash pan including an offset portion constituting a mixing chamber for fuel gas, and an apron portion integral with the

burner depending into the flash pan and forming a partition between said flash pan and the mixing chamber.

21. A flash pan and burner construction for heating units, comprising an annular flash pan having a central draft opening therein and an annular burner disposed above the flash pan, said burner having a plurality of passageways therein for conducting fuel gas to the burner orifices, a fuel gas injector arranged above the bottom of the flash pan and a deflector depending into the flash pan and directing entering gas into a plurality of such passages.

22. A flash pan and burner construction for heating units, comprising an annular flash pan having a central draft opening therein and an annular burner disposed above the flash pan; said flash pan including an offset portion constituting a mixing chamber for fuel gas; a gas injector nozzle discharging into said chamber, said chamber having openings in one wall thereof through which air is adapted to be drawn by the action of the injector.

23. A flash pan and burner construction for heating units, comprising an annular flash pan having a central draft opening therein and an annular burner disposed above the flash pan, said flash pan and burner constituting an integral structure; said flash pan including an offset portion constituting a mixing chamber for fuel gas; a gas injector nozzle discharging into said chamber, said chamber having openings in one wall thereof through which air is adapted to be drawn by the action of the injector and manually controlled dampers associated with said openings.

24. A gas producer and heating unit, including means for generating steam, a burner below the steam generator and a flash pan under the burner; a reaction chamber in the form of a downwardly draining coil of pipe surrounding the steam generator; means operable when the burner is in operation for supplying partially vaporized oil and steam to the reaction chamber and for injecting the products of reaction with air to the burner, and means operable when the burner is not in operation for gravitationally feeding oil through the reaction chamber to the flash pan.

25. A gas producer and heating unit, including means for generating and drying steam, a burner below the steam generator and a flash pan under the burner; a downwardly draining reaction chamber surrounding the steam generator; means operable when the burner is in operation for supplying partially vaporized oil and superheated steam to the reaction chamber and for supplying the products of reaction to the burner, and means operable when the burner is not in operation for gravitationally feed-

ing oil through the reaction chamber to the flash pan, and a float control in the flash pan controlling said last mentioned means.

26. In a gas producer and heating unit, a steam generator and drier, comprising a vessel having an integral partition wall dividing it into a lower boiling chamber and an upper steam drying chamber, said wall having an opening therein affording restricted communication between the chambers, a burner below said vessel for imparting heat to the water in the lower chamber, and heat absorbing means exposed to the heat of said burner for maintaining said upper chamber at a temperature above boiling point.

27. In a gas producer and heating unit, a steam generator and drier, comprising a pot, an integral partition wall dividing the pot into a lower boiling chamber and an upper steam drying chamber, said wall having an opening therein affording restricted communication between the chambers, a collecting tube integral with the pot and extending into the drying chamber, said tube having apertures therein to permit dried steam to escape into the tube from the drying chamber.

28. In a gas producer and heating unit, a steam generator and drier, comprising a cast iron pot having an integral partition wall dividing the pot into a lower boiling chamber and an upper steam drying chamber, said wall having an opening therein affording restricted communication between the chambers and an outwardly projecting flange at the upper end of the pot, for the purpose described.

29. In a gas producer and heating unit, a steam generator and drier, comprising a round pot adapted for disposition above an annular burner, an integral partition wall dividing the pot into a lower boiling chamber and an upper steam drying chamber, said wall having an opening therein affording restricted communication between the chambers and an outwardly flaring flange at the upper rim of the pot directly in the path of flame and hot products of combustion from the burner.

30. A gas producer and heating unit, comprising a burner, a round bottomed pot constituting a steam generator and drier, an integral partition wall dividing the pot into a lower boiling chamber and an upper steam drying chamber, said wall having an opening therein affording restricted communication between the chambers, a superheater tube integral with the pot and extending into the drying chamber, said tube having apertures therein to permit dried steam to escape into the tube from the drying chamber; a spiral reaction chamber coaxial with the pot and surrounding the same, said pot and reaction chamber being directly in the path of flames and hot products of combustion.

tion from the burner; means for intimately mixing oil with superheated steam within the reaction chamber to form a fuel gas for the burner.

31. In a gas producer and heating unit, a steam generator and superheater, including an annular burner, a round bottomed pot coaxial with the burner, a partition wall dividing the pot into a lower boiling chamber and an upper steam chamber, said wall having an opening therein affording restricted communication between the chambers.

32. In a gas producer and heating unit, a steam generator and superheater, including an annular burner, a round bottomed pot coaxial with the burner; a superheated steam outlet tube integral with the pot and extending into the upper part thereof, said tube having apertures therein to permit steam to escape into the tube.

33. In a gas producer and heating unit, a steam generator and superheater, including an annular burner, a round bottomed pot coaxial with the burner, an integral partition wall dividing the pot into a lower water chamber and an upper steam chamber, said wall having an opening therein affording restricted communication between the chambers; a superheated steam outlet tube integral with the pot and extending into the drying chamber, said tube having apertures therein to permit dried steam to escape into the tube from the drying chamber.

34. In a water gas producer and burner apparatus, means for burning the gaseous product and applying the heat thereof to operate the producer, the producer apparatus thus heated including a steam generator and a tubular retort formed as a coil encircling the generator and arranged for drainage from an upper inlet toward a lower outlet, in combination with a steam injector for injecting vaporized oil through the inlet of the retort and means for delivering products of the reaction of the steam and oil, from said retort to said burner; said retort including metal exposed to the steam and oil therein and said metal being of the group

adapted to promote characteristic reactions of hydrocarbons with steam to produce water 50 gas.

35. In a gas producer and burner apparatus, means for burning the gaseous product of the apparatus and applying the heat thereof to operate the producer, the producer apparatus thus heated including a steam generator having a lower boiling chamber and an upper steam drying chamber with a contracted opening affording restricted communication between them and a tubular retort formed as a coil encircling the generator, spaced apart therefrom more widely at the bottom than at the top and arranged for drainage from an upper inlet toward a lower outlet, in combination with a steam injector for discharging steam from said generator and injecting a steam-oil mixture lengthwise into the upper end of said tubular retort, and means for delivering products of the reaction of the steam and oil from 70 the retort to said gas burning means and for discharging hot products of the combustion upward between said steam generator and said retort coil.

36. In a gas producer and burner apparatus, means for burning the gaseous product of the apparatus and applying the heat thereof to operate the producer, the producer apparatus thus heated including a steam generator and a tubular retort formed as a coil 75 encircling the generator but spaced apart therefrom and arranged for drainage from an upper inlet toward a lower outlet, in combination with a steam injector for discharging steam from said generator and 85 injecting a steam-oil mixture lengthwise into the upper end of said tubular retort, means for delivering products of the reaction of the steam and oil from the retort to said gas burning means to heat both said steam 90 generator and said retort.

Signed at New York, in the county of New York, and State of New York, this 5th day of April, A. D. 1924.

EDWARD O. BENJAMIN.
